UNITED STATES PATENT OFFICE.

DONALD H. BUTLER, OF EL RENO, OKLAHOMA.

DRAFT-GENERATOR.

1,121,471.

Specification of Letters Patent. Patented Dec. 15, 1914.

Application filed January 14, 1914. Serial No. 812,127.

To all whom it may concern:

Be it known that I, DONALD H. BUTLER, a citizen of the United States, residing at El Reno, in the county of Canadian and State of Oklahoma, have invented new and useful Improvements in Draft-Generators, of which the following is a specification.

This invention relates to draft generators for steam boilers, the object of the invention being to provide in connection with a steam boiler, a blower or fan including driving connections and a discharge nozzle arranged for manual operation and adapted to deliver a blast of air in an upward direction in or adjacent to the bottom of the smoke stack for the purpose of inducing a pronounced draft in the proper direction before there is any steam pressure in the boiler.

With the above and other objects in view, the invention consists in the novel construction, combination and arrangement of parts, as will hereinafter be more fully described, illustrated and claimed.

In the drawings: Figure 1 is a side elevation of a steam boiler showing the draft generator of this invention applied thereto. Fig. 2 is a horizontal section through the attachment. Fig. 3 is a detail perspective view of the gear case and fan casing detached from the boiler, showing also the operating crank and tumbling shaft.

Referring to the drawings 1 designates an ordinary steam boiler provided with the usual stack 2 and dome 3.

In carrying out the present invention I employ a fan casing 4 which is disposed vertically when applied to the boiler 1 as shown in Fig. 1, said casing being attached to one end of a gear case designated generally at 5 and comprising the separable sections 5 and 6 one of which may be removed to afford access to the mechanism contained therein.

From the discharge nozzle 7 of the fan casing 4, a pipe 8 leads into the stack adjacent to the base thereof as indicated in Fig. 1, a blast nozzle 9 being provided at the discharge end of said pipe 8 so as to direct the blast of air upwardly through the stack from the base thereof thereby inducing a draft through the fire tubes or flues of the boiler for the purpose of expediting the generation of steam in said boiler.

The shaft 10 of the fan has a worm 11

fast thereon, said shaft being journaled in bearings 12 in the gear case A. Meshing 55 with the worm 11 is a worm wheel 13 on the shaft of which is a spur pinion 14 which is driven by a spur wheel 15 on the shaft of which is a spur pinion 16 that meshes with an initial driving spur wheel 17. 60

The wheel 17 in addition to the spur gear face is provided with a bevel gear face 18 which meshes with and is driven by a bevel pinion 19 fast on the inner section 20 of a tumbling shaft. This tumbling shaft is provided with one or more additional sections 21 and 22 to enable said shaft to extend laterally to one side of the steam dome 3, the final section of said tumbling shaft being provided with a hand crank 23 by means of 70 which the draft generator may be manually operated at such times as may be necessary to increase the draft for the purpose stated.

The draft generator hereinabove described is, by reason of the construction set forth, particularly adapted for use as an attachment to steam boilers and is fastened in place by merely securing the section 5 of the gear case to the top of the boiler as 80 shown in Fig. 1 and forming a hole adjacent to the base of the stack 2 through which the discharge pipe 8 is inserted. The tumbling shaft may lead to either side of the steam dome 3 and said shaft may be of such length 85 as to locate the operating crank 23 at any desired or convenient point.

What I claim is:—

A draft generating attachment for steam boilers, comprising a rotary fan, a discharge 90 pipe leading off tangentially therefrom, a blast nozzle located in the base of the smoke stack with which said discharge pipe communicates, a flat and substantially rectangular gear case to one end of which the fan 95 casing is attached, and manually operable means for driving and supporting said fan embodying a train of speed increasing gears journaled in and inclosed by said gear case and operatively connected with the fan 100 shaft, the initial gear having a bevel gear face in addition to its speed gear face, and an operating shaft having a plurality of tumbling joints therein and provided at one end with an operating crank and at its other 105 end with a bevel pinion meshing with said

bevel gear face of the initial speed gear, the said gear case being supported in parallel relation to the shell of the boiler between the smoke stack and steam dome, said tumbling shaft extending to one side of said steam dome and back to the furnace end of the boiler.

In testimony whereof I affix my signature in presence of two witnesses.

DONALD H. BUTLER.
